CLAIM

I claim the ornamental design for a cribbage board, as shown and described.

DESCRIPTION

FIG. 1 is a top perspective view of a cribbage board showing my new design;

FIG. 2 is a bottom perspective view thereof, showing the scoring peg storage compartment lid in the closed position; FIG. 3 is a bottom perspective view thereof, showing the scoring peg storage compartment lid rotated to the open position;

FIG. 4 is a top plan view thereof;

FIG. 5 is a front elevational view thereof, the rear elevational view being a mirror image thereof;

FIG. 6 is a bottom plan view thereof;

FIG. 7 is a right-side elevational view thereof, the left-side elevational view being a minor image thereof; and,

FIG. 8 is a top plan view of the cribbage board according to a second embodiment, wherein the bottom, front, rear and sides are the same as what is disclosed for the embodiment of FIG. 1, as shown in FIGS. 2, 3, 5, 6 and 7.
